UNITED STATES PATENT OFFICE.

WILLIAM N. SELIG, OF CHICAGO, ILLINOIS, ASSIGNOR TO SELIG POLYSCOPE COMPANY, OF CHICAGO, ILLINOIS, A CORPORATION.

MACHINE FOR EXHIBITING AND TAKING PICTURES.

SPECIFICATION forming part of Letters Patent No. 712,462, dated October 28, 1902.

Application filed September 6, 1900. Renewed March 27, 1902. Serial No. 100,294. (No model.)

To all whom it may concern:

Be it known that I, WILLIAM N. SELIG, a citizen of the United States, residing at Chicago, in the county of Cook and State of Illinois, have invented certain new and useful Improvements in Machines for Exhibiting and Taking Pictures, of which the following is a specification.

The invention relates to that class of machines for exhibiting and taking pictures especially designed for use in the display of what are known or termed "moving" pictures, which machines have a variety of names or designations. It is well known that in order to obtain the best results machines of this class should have a positive and reliable movement as regards the timing of the parts, so as to bring the picture properly in view to be projected, it being understood that the pictures are taken under the same conditions.

The objects of the present invention are to insure a positive and reliable feed of the pictures into the line of projection, to improve the construction and operation of the feeding mechanism and the film ribbon or strip on which the pictures are taken, to positively and effectually cut off and renew or supply the light at the proper time in relation to the feed of the pictures and so as to have the cut-off occur simultaneously with the feed of a new picture into place and to have the renewal of the light occur as the picture is in place to be projected or at the time the picture is taken, to improve the construction and operation of the cut-off in its relation to the feed mechanism of the strip and pictures, and to improve generally the construction and operation of the machine as a whole.

The invention consists in the features of construction and combinations of parts hereinafter described and claimed.

In the drawings illustrating the invention, Figure 1 is a front elevation with the upper reel for the film-strip partly broken off and the lower reel for such strip removed; Fig. 2, a side elevation of the driving pulley or wheel for the lower reel of the film-strip; Fig. 3, a rear elevation of the machine with the upper reel for the film-strip broken off and the lower reel removed; Fig. 4, a perspective view of

the rake or draw-arm for advancing the film-strip a predetermined distance at each advance; Fig. 5, a side elevation of the machine with the upper reel for the film-strip partly broken off; Fig. 6, a sectional elevation on line 6 of Fig. 1 and showing also in dotted lines the frame or support for the lens and some of the operating devices swung forward to permit access to the main frame or support; Fig. 7, a rear elevation of the support or frame carrying the lens-tube and some of the operating devices; Fig. 8, a sectional elevation from the rear of the lens-tube support and its adjusting - lever; Fig. 9, a sectional plan view on line 9 of Fig. 1 of the upper power-transmitting shaft for the feeding or engaging disks or wheels of the film ribbon or strip; and Fig. 10, a sectional plan view on line 10 of Fig. 1, showing the main power-shaft and its wheels.

The machine is to have a main frame or support A, mounted on a base A', the frame and its base being made of metal or other suitable material. A second frame or support B for the lens-tube and other appliances is attached to the main frame or support on the front side by a flap or butt-piece B', secured to the main frame or support by screws or otherwise, with a hinge connection b between the second frame or support and the flap or butt, so that the frame or support can be dropped forward, as shown by the dotted lines in Fig. 6. The second frame or support is held upright against the main frame or support by a catch a, having a finger-piece or arm a' and pivotally attached to the main frame by a pin or pivot a', so that its acting end can be made to overlap the edge of the frame or support B and lock said frame or support in its operating position.

The frame or support B has thereon guide-rods C, the ends of which are entered in ears c, projected out from the side pieces of the frame, in which ears the ends of the guide-rods are locked and held by set-screws c' or in any other suitable manner. A plate D is mounted on the guide-rods so as to slide thereon, for which purpose the plate has ears d, through which the guide-rods pass. This plate has an annular rim or wall D' on its rear face, and its front face has an annular ring

d^3 with a screw-thread for the attachment of the lens-tube D^2 , which tube is of any usual and well-known form of construction, and the end wall of the rear rim or annular wall has a sight-opening d' , which, as shown, is of a rectangular form, but might be of other suitable or desired form. The lens supporting and carrying plate D is moved up and down on the guide-rods in the construction shown 10 by means of a lever E , pivotally attached by a pin or pivot e to an ear or lug d^2 on the upper end of the supporting-plate and having at one end a slot e' for the passage of a pin or pivot e^2 , which is entered into a block or 15 slide c^2 , mounted and adjustable on one of the guide-rods and locked and held when adjusted by a set-screw or otherwise. The pin or pivot e^2 forms a fulcrum, so that by moving the free end of the lever up or down the 20 carrying-plate will be raised or lowered, as may be required or necessary, to bring the lens-tube in proper relation for projecting and displaying or for taking a picture.

The picture ribbon or strip of film is wound 25 onto an upper reel F of suitable construction and having a hub or spool mounted on a supporting-rod F' , and, as shown, the outer disk or head of the reel has a stud or lug f , attached to which is a spring f' , the free end of 30 which engages with grooves f^2 in the end of the supporting-rod, so as to hold the reel against an adjustable collar f^3 , movable on the rod and locked and held when adjusted by a set-screw f^4 or by other suitable means. The 35 film ribbon or strip runs from the upper reel to a lower reel G , mounted on a shaft or spindle C' , and, as shown, the outer disk or head of this reel has a stud or lug g , attached to which is a spring g' , the free end of which 40 engages with a groove g^2 in the end of the shaft or spindle and holds the reel in place. The spindle G' at its inner end has a square shoulder g^3 , which enters a square recess in the reel disk or head or the hub or spool of 45 the reel and locks the reel on the spindle, so as to revolve therewith, and, as shown, the reel is held against end play inward on its shoulder by a collar or ring g^4 on the shaft or spindle. The shaft or spindle G' of the lower 50 reel is mounted in suitable heads or bearings on the ends of the arms of a fork or stirrup G^6 , attached to a post or upright G^7 , secured to the base of the machine, and has attached thereto intermediate of its bearings a grooved 55 pulley-wheel G^2 , over which a driving-belt G^3 is driven from a grooved pulley-wheel G^4 on the main driving-shaft. The pulley-wheel is connected with the shaft or spindle by a ratchet-wheel G^5 , fixed to the shaft or spindle 60 by a set-screw or otherwise and having its teeth engaged by a pawl or ratchet g^5 , pivotally mounted on the side face of the pulley and held in engagement by a spring g^6 , attached at one end to the side face of the pulley, which connection causes the pulley to 65 drive the shaft or spindle and allows the shaft or spindle to have a reverse rotation inde-

pendent of the pulley. The upper reel is loose on its supporting rod or shaft and is free to revolve through the action of the ribbon or strip of film as it unwinds therefrom. 70

The film ribbon or strip H , having the pictures thereon in regulated spaces or intervals forming distinct panels H' , each containing a picture, is attached at one end to the upper reel and at its other end to the lower reel, so that with the revolving of the lower reel the film ribbon or strip unwound from the upper reel will wind onto the lower reel. This ribbon or strip has on each side edge or 80 border h' a series of perforations h at regular distances apart longitudinally of the ribbon or strip, forming a ribbon or strip having perforated side edges or borders with the perforations equidistant one from the other on the 85 respective edges or borders. The film ribbon or strip must be unwound from the upper reel with regularity and under conditions which will maintain and hold it momentarily stationary and taut at the display-opening or 90 point of projection for the picture, and for this reason the unwinding of the strip from the upper reel must be under a regulated and perfect control. This control is secured by having the strip engaged and operated on by 95 feed wheels or disks located on the secondary frame or support, one pair or set above and one pair or set below the limit of movement of the lens-tube. The upper pair or set of feed wheels or disks I each has on its periphery a series of teeth or projections i , spaced a distance apart corresponding to the spaced distance between the perforations h , so that with the rotation of the wheels or disks the teeth projections or lugs i thereon will 105 engage with the perforations h of the film ribbon or strip and control the advance of the strip or the movement thereof in either direction. The pair or set of feed wheels or disks I are attached to an outer tube or hollow shaft I' by means of keys i' or in any other suitable manner, as shown in Fig. 9, and the outer tube or hollow shaft at each end is of a less diameter, forming journals I^2 for the tube or hollow shaft, each mounted 110 in a suitable box or bearing j on the upper projecting lugs or ears c of the frame or support B , so that when engaged by its driving spindle or shaft the outer tube or hollow shaft is free to revolve. The outer tube or hollow 115 shaft I' is mounted on an inner spindle or shaft J , which extends at each end beyond the ends of the journals of the outer tube or hollow shaft. The inner shaft or spindle J at one end has a head j' , between which and 120 the end of the journal I^2 is a coil-spring j^2 . The spindle or shaft J at its opposite end in the construction shown has a cross-pin j^3 , arranged to engage with a notch, recess, or seat i^2 in the end of the journal I^2 , so as to lock 125 the outer tube or hollow shaft and the inner driving spindle or shaft together for the revolving of the inner spindle or shaft to revolve the outer tube or hollow shaft. The two shafts 130

can be disengaged by forcing the inner spindle or shaft endwise against the resistance of the coil-spring, so as to release the pin from engagement, which allows the inner spindle 5 or shaft to revolve without imparting rotation to the outer tube or hollow shaft and with the release of the end pressure on the inner spindle or shaft the coil-spring l^2 acts and reengages the two shafts, so that they will 10 revolve together.

The lower pair or set of feed wheels or disks K has on its periphery a series of teeth or 15 projections k , spaced a distance apart corresponding to the spaced distance between the perforations h , so that with the rotation of the wheels or disks the teeth, projections, or lugs k thereon will engage with the perforations h of the film ribbon or strip and control the advance of the strip or the movement 20 thereof in either direction. The construction of the two sets or pairs of wheels or disks is the same, each having the same diameter and the same number of teeth, projections, or lugs, by which arrangement it will be seen 25 that the ribbon or strip of film between the upper set or pair of feed wheels or disks and the lower set or pair of feed wheels or disks moves in unison corresponding to the travel of the wheels or disks, insuring a reliable and 30 positive feed or advance of the ribbon or strip between the upper and lower feed wheels or disks by reason of such feed or advance being produced and controlled by the engagement of the teeth or projections of the wheels 35 or disks with the perforations on the borders of the ribbon or strip, so that the feed or advance occurs with the rotation of the wheels or disks and the engagement of the teeth or pins and the perforations, which insures a uniformity of the feed or advance or movement 40 in either direction.

The lower wheels or disks are attached to an outer tube or hollow shaft K', having at each end a journal K ^{2} , which shaft has the 45 wheels or disks K mounted thereon the same as the wheels or disks I are mounted on the outer shaft or tube J. The outer tube or hollow shaft K' is mounted on an inner spindle or shaft L, extending through and projecting 50 beyond the journals K ^{2} of the outer tube or hollow shaft, which journals are mounted in suitable boxes or bearings l on the frame or support B. The inner spindle or shaft L at one end has a head l' , between which and 55 the end of the journal K ^{2} around the inner spindle or shaft is a coil-spring l^2 . The other end of the spindle or shaft L has a cross-pin l^3 to engage with a notch or recess k^2 in the end of the journal K ^{2} . The shafts are locked 60 to rotate together by the engagement of the pin l^3 with the notch or recess k^2 and are unlocked, so as to prevent rotation of the outer tube or shaft by forcing the inner spindle or shaft endwise against the spring l^2 until the 65 cross-pin is disengaged from its notch or recess, permitting the inner spindle or shaft to rotate without revolving the outer tube or

shaft, and with the release of the end pressure the cross-pin and notch or recess are reengaged, so that the two shafts will revolve 70 together. The inner spindle or shaft L has thereon a sprocket gear-wheel L', by means of which the shaft is driven, as hereinafter described. The inner end of the spindle or shaft L has secured thereto a sprocket-wheel 75 L ^{2} , over which a sprocket-chain L ^{3} runs, which chain also runs over a sprocket-wheel L ^{4} on the end of the spindle or shaft J, so that with the rotation of the spindle or shaft L the spindle or shaft J will be rotated, imparting 80 rotation simultaneously to the two sets or pairs of feed wheels or disks I and K for the two sets or pairs to run uniformly and at the same speed.

The main driving-shaft M is supported in 85 suitable bearings on the base of the machine, and this shaft at its outer end has a gear-pinion m, which meshes with a large driving-gear M ^{4} , the hub of which is mounted on a spindle M ^{5} , extending out from the main 90 frame or support. The hub of the gear is elongated and has mounted thereon a sleeve or socket m ^{4} , having therein a slot m ^{3} , with which a stud or pin m ^{2} on the hub of the gear engages and connects the hub and the sleeve 95 with each other, so as to permit of a slight independent movement of the sleeve when reversing motion. The sleeve has formed therewith a crank M ^{6} , on which is a handle M ^{7} , by means of which power is applied to 100 drive the gear M ^{4} and revolve the pinion m to drive the main power-shaft M. The main power-shaft in the arrangement shown has thereon a small balance or power-accumulating wheel M' to give steadiness to the rotation of the shaft. This shaft M ^{4} has mounted thereon and fixed thereto the grooved pulley G ^{1} for the driving-belt G ^{3} and also a sprocket-wheel M ^{2} , over which and around 105 the sprocket-wheel L' a sprocket-chain M ^{3} runs for driving the wheel L' and imparting rotation to the shaft L, revolving the feed wheels or disks K and through the chain L ^{3} , sprocket-wheels L ^{2} and L ^{4} driving the shaft J and imparting rotation to the feed wheels 110 or disks I.

The inner end of the main driving-shaft has fixed thereto a crank N', connected with which, by a wrist pin or pivot n ^{1} , is an arm or bar N, having in its body a curved slot n, 120 as shown in Fig. 4, through which a pin or pivot n ^{4} passes with its end entered and held in an ear or boss n ^{5} on the back of the main frame or support. The upper end of the arm or bar N carries a cross-rod N ^{2} , at each end 125 of which is a plate n ^{3} , each plate having on its free end teeth or projections n ^{6} , set or spaced at the same distance apart as the spaced distance between the perforations h of the film ribbon or strip, so that the teeth, 130 projections, or points n ^{6} can be made to engage with the perforations of the ribbon or strip. The arm or bar N has a vertical play and also an oscillating or swinging movement

on its pin or pivot, and these two movements combined give the acting end, having the cross-rod N^2 , an up-and-down travel and an in-and-out throw, by means of which the end plates n^2 are projected into slots N^3 in the web or body of the frame or support A to have the teeth, projections, or points n^3 engage with a corresponding number of perforations in the ribbon or strip, and when so engaged the downward movement of the arm or bar carries with it the end plates n^2 , which act to draw down the strip or ribbon. The downward movement of the strip or ribbon continues until the limit of down-thrust of the rod or bar is reached, at which time the arm or bar is given an outward swing at its upper end, withdrawing the plates n^2 , with their teeth, projections, or points, from the slots and disengaging the ribbon or strip, which remains motionless with a picture central of the sight-opening d' in the end plate of the lens-tube and central of an opening or window A^2 in the main frame or support and an opening or window B^2 in the second frame or support which carries the lens-tube. The outward movement of the upper end of the arm or bar continues until the limit of the throw is reached, which limit is also the limit of the downward thrust of the arm or bar, and when this point is reached the arm or bar begins its upward thrust, which thrust continues until its limit is reached, at which point the upper end of the arm or bar is moved inward for the end plates n^2 at the terminal point of the upward thrust and inward movement to be again entered into the slots N^3 and have the teeth, perforations, or points engage with the perforations of the ribbons, and during such upward thrust and forward throw of the arm or bar the ribbon remains stationary or in a fixed position to display the picture which is in front of the sight-opening. These movements of the arm or bar will continue as long as the display of pictures is to be made by simply revolving the main shaft, and with each downthrust of the arm or bar the ribbon or strip is advanced so as to bring into view a new picture, at the same time withdrawing the preceding picture, and the distance the ribbon or strip is moved in each instance is always the same, because the thrust and throw of the arm or bar is the same distance in each case by reason of the rotation of the crank, which gives the required raking or drawing movement to the arm or bar.

It is necessary that during the periods of transition, in which a new picture takes the place of the preceding one, the light should be momentarily shut off in order to prevent the run of one picture into another in a manner to cause confusion and a bad effect. This shut-off should act instantaneously both in shutting off and admitting the light in order to give the best effects. A shut-off for this purpose is provided, consisting of a disk O, mounted on a spindle projecting out from the

rear face of the main frame or support and having attached thereto by screws o or otherwise a semicylindrical disk or plate O', the lines of which are cut so as to present a defined sharp edge o' on each side, which edges act with the rotation of the disk or plate to cut off the light as the advance edge reaches and passes the window or opening for the picture and to admit the light as the rear edge reaches and passes the window or opening for the picture. The rotation of the disk to present the edges properly in relation to the window or opening to cut off and admit the light should be one that will produce the cut-off effect when the rake or claw is performing its work of presenting a new picture in front of the opening or window and that will bring the light-admitting edge of the disk or plate to pass the window when the rake or claw has completed its work and the picture is in front of the opening or window. The opening between the two defining edges is one to admit the light for the length of time required to project or throw the picture properly, which is the time that the picture remains stationary while the rake or claw is making its backward, upward, and forward movement to engage with the ribbon or strip to advance the next picture. It will thus be seen that the rake or claw and the shade disk or plate coöperate together—that is, the shade disk or plate is in position to shut off the light while the rake or claw is operating to bring a new picture into view and the shade disk or plate is in position to admit the light while the rake or claw is returning to engage the ribbon or strip and advance a new picture.

The ribbon or strip, at the point of engagement of the rake or claw therewith, is held so as to insure the engagement by means of flat bow-shaped springs P—one on each side—each spring engaging the border or edge of the ribbon or strip in line with the advance of the rake or claw through the slots, and these springs are secured to a cross-bar b' of the frame or support B. The ribbon or strip passes from the upper reel downward between the frame or support B and the frame or support A, back of the pressure-springs P and back of the feed wheels or disks I and K, as shown in Fig. 6. The ribbon or strip is free to slack somewhat between the upper feed wheels or disks and the windows or openings of the frames or supports and is held against self-slipping past the windows or openings by the springs P. Below the springs and above the lower feed wheels or disks the ribbon or strip is free to slack somewhat, and to prevent the slack from falling too far and interfering with the operation of the lower feed wheels or disks a rest or support b² is provided on the frame B, and below the lower feed wheels or disks the frame has an outwardly-projecting ledge b³, which assists in maintaining the engagement of the ribbon or strip with the wheel by giving it a slightly forward and downward inclination.

The ribbon or strip after it leaves the lower

feed disk or wheel passes under a roller H^2 , mounted on a spindle H^3 , carried by one arm H^4 of a bell-crank or L lever, which lever is pivoted to an arm or bracket h^7 , extending out from the main frame or support by a pin or pivot h^4 . The other arm H^5 of the lever carries a roller h^6 , mounted on a spindle h^5 , and this roller engages with the driving-belt G^3 and acts to some extent as a tightener.

10 The bell-crank or L lever is held in normal position by a coil-spring h^8 , one end of which is attached to the lever and the other to the base of the machine, which spring permits the lever to rise in case of too much tension 15 on the ribbon or strip. The ribbon or strip is kept from injury in being advanced by a backing or lining of textile fabric h^9 on the face of the main frame or support in the pathway of travel for the ribbon or strip. If 20 desired, the window or opening A^2 can be provided with a setting Q , of glass or other transparent material, held in the opening by springs q , so as to be removable, or otherwise secured in place.

25 It will be seen that the ribbon is free to unwind from the upper reel and is unwound and carried down or advanced by the action of the upper feed wheels or disks. The ribbon or strip in such movement is free to flex or bend above the lens-tube, but is held taut and straight in its passage between the windows or openings, so as to throw or project the picture in a proper manner. The ribbon or strip below the lens-tube is held against 30 self-slipping by the pressure-springs, which also form a backing to insure the engagement of the ribbon by the rake or claw. The rake or claw by its action draws down or advances the ribbon positively a distance equal to the 35 space occupied by the picture, and such drawing down or advance is facilitated by the flex or bend below the upper feed-wheel. The ribbon or strip is moved downward or advanced after its release by the rake or claw 40 through the action of the lower feed wheels or disks, and from the feed-wheel the ribbon is unwound onto the lower reel by the revolving of such reel. The feature of allowing the 45 ribbon or strip to flex or bend above the lens-tube and below the rake or claw allows the rake or claw to operate without straining the ribbon and allows the lower feed wheels or disks to operate without strain or draw on the ribbon or strip, by which arrangement injury 50 to the ribbon or strip from the action of the feed wheels or disks and of the rake or claw is effectually guarded against. The ribbon or strip is positively engaged by the upper and lower feeds and is held by the feeds against 55 travel except by the action of the feeds, so that it is fed or advanced under and by a positive engagement with its feed. The ribbon or strip is given a positive and regular intermittent feed, by which it is acted on and fed 60 forward or advanced under and by a positive engagement. This operation of a positive feed, continuous and intermittent in charac-

ter, gives the most perfect and reliable results, as the ribbon or strip is under a regulated control and can only be advanced or moved as it is acted upon by the feed, the intermittent feed and the intermittent shade for cutting off and admitting light having a coacting relation by which as a picture is being advanced the light is cut off and with the cessation of the advance the light is admitted, thus preventing the running of one picture into another to create confusion and giving each picture a prominent projection and display. These several features of construction 75 and operation are found combined and operative in the machine of this invention and add to the utility of machines for exhibiting and taking pictures.

What I regard as new, and desire to secure 85 by Letters Patent, is—

1. The combination in a picture exhibiting and taking machine, of an upper feed and a lower feed for the picture ribbon or strip, both feeds positively engaging the picture 90 ribbon or strip outside of the line of the picture on each side and each feed comprising a rotatable shaft, a sleeve mounted on the shaft and having the shaft endwise movable therein and feed-disks fixed on the sleeve to 95 engage the edges of the picture ribbon or strip, an interlock between each shaft and the sleeve mounted thereon, a sprocket-wheel on the end of each shaft, a sprocket-chain running over the sprocket-wheels, and a driving means for the lower rotatable shaft for 100 operating both feeds simultaneously, substantially as described.

2. The combination in a picture exhibiting and taking machine, of a hinged frame or support, an upper feed and a lower feed for the picture ribbon or strip, both feeds carried by the hinged frame or support and both positively engaging the picture ribbon or strip and each feed comprising a rotatable shaft, a sleeve mounted on the shaft and having the shaft endwise movable therein and feed-disks fixed on the sleeve to engage the edges of the picture ribbon or strip, an interlock between 115 each shaft and the sleeve mounted thereon, a sprocket-wheel on one end of each shaft, a sprocket-chain running over the sprocket-wheels, and a driving means for the lower rotatable shaft for operating both feeds simultaneously, substantially as described. 120

3. The combination in a picture exhibiting and taking machine, of a main frame, a secondary frame or support mounted on the main frame and hinged thereto at its lower end, an upper feed and a lower feed for the picture ribbon or strip, both feeds carried by the secondary frame or support and both positively engaging the picture ribbon or strip and each feed comprising a rotatable shaft, a sleeve mounted on the shaft and having the shaft endwise movable therein and feed-disks fixed on the sleeve to engage the edges of the picture ribbon or strip, an interlock between 130 each shaft and the sleeve mounted thereon, a

sprocket-wheel on one end of each shaft, a sprocket-chain running over the sprocket-wheels and a driving means for the lower rotatable shaft for operating both feeds simultaneously, substantially as described.

4. The combination in a picture exhibiting and taking machine, of a main frame, a secondary frame or support mounted on the main frame and hinged thereto at its lower end, an upper feed and a lower feed for the picture ribbon or strip, both feeds carried by the secondary frame or support and both positively engaging the picture ribbon or strip, each feed comprising a rotatable shaft, a sleeve mounted on the shaft and having the shaft endwise movable therein and feed-disks fixed on the sleeve to engage the edges of the picture ribbon or strip, an interlock between each shaft and the sleeve mounted thereon, a sprocket-wheel on one end of each shaft, a sprocket-chain running over the sprocket-wheel, a driving means for the lower rotatable shaft operating both feeds simultaneously, an intermittent feed mounted on the main frame and operating between the upper feed and the lower feed and positively engaging the picture ribbon or strip and comprising two companion plates, each having a face for engagement with the edge of the picture ribbon or strip, a cross-rod supporting the plates one at each end thereof and a reciprocating and oscillating rigid arm or bar carrying the cross-rod, and means for giving the arm or bar its reciprocating and oscillating movements, substantially as described.

5. The combination in a picture exhibiting and taking machine, of an intermittent feed positively engaging the picture ribbon or strip on the border edges thereof on each side and comprising two companion plates, each having a face for engagement with the border edge of the picture ribbon or strip, a cross-rod supporting the plates one at each end thereof, a reciprocating and oscillating rigid arm or bar carrying the cross-rod, a fixed bearing on which the arm or bar slides and rocks, and means for giving the arm or bar its reciprocating and oscillating movements, substantially as described.

6. The combination in a picture exhibiting and taking machine, of a picture ribbon or strip having on each side an edge border, a pair of feed wheels or disks positively engaging the edge borders of the picture ribbon or strip, a sleeve having the wheels or disks fixed thereon, a rotatable shaft on which the sleeve is mounted and endwise slidably in the sleeve, an interlock between the shaft and sleeve, a sprocket-wheel on the end of the shaft, and means for driving the sprocket-wheel and continuously revolving the feed wheels or disks to advance the picture ribbon or strip, substantially as described.

7. The combination in a picture exhibiting and taking machine, of an intermittent feed positively engaging the picture ribbon or strip on the border edges thereof on each side and

comprising two companion plates, each having a face for engagement with the border edge of the picture ribbon or strip, a cross-rod supporting the plates, one at each end thereof, a reciprocating and oscillating rigid arm or bar carrying the cross-rod and having in its body a cam-slot, a fixed bearing entered into the cam slot and on which the arm or bar slides and rocks, and a revoluble disk having an end of the arm or bar connected therewith whereby the revolving of the disk will give the arm or bar its reciprocating and oscillating movements, substantially as described.

8. The combination, in a picture exhibiting and taking machine, of an intermittent feed positively engaging the picture ribbon or strip on the border edges thereof on each side and comprising two companion plates, each having a face for engagement with the border edge of the picture ribbon or strip, a cross-rod supporting the plates, one at each end thereof, a reciprocating and oscillating rigid arm or bar carrying the cross-rod and having in its body a cam-slot, a fixed bearing on which the arm or bar slides and rocks, a disk having an end of the arm or bar connected thereto at one side of the axial center, and a revoluble shaft carrying the disk for giving the arm or bar its reciprocating and oscillating movements, substantially as described.

9. The combination, in a picture exhibiting and taking machine, of a picture ribbon or strip having the border edges thereof on each side provided with perforations, two companion plates, each having an acting face provided with pins or projections to engage the perforated edges of the picture ribbon or strip, a cross-rod supporting the plates, a reciprocating and oscillating rigid arm or bar carrying the cross-rod, a cam-slot in the body of the arm or bar, a fixed bearing passing through the cam-slot and on which the arm or bar slides or rocks, and a revoluble disk having an end of the arm or bar connected therewith at one side of the axial center of the disk for reciprocating and oscillating the arm or bar to move the two companion plates and intermittently advance the picture ribbon or strip, substantially as described.

10. The combination in a picture exhibiting and taking machine, of a picture ribbon or strip having on each side an edge border provided with perforations spaced equidistant apart, a pair of upper feed wheels or disks each wheel or disk provided with teeth or projections spaced equidistant apart corresponding to the spacings of the perforations in the edge borders of the picture ribbon or strip, a sleeve having the feed wheels or disks fixed thereon, a rotatable shaft for each sleeve endwise slidably therein, an interlock between the shaft and sleeve, means for revolving the shaft and causing the teeth or projections to engage with the perforations to continuously advance the ribbon or strip, a pair of plates, each plate having teeth or projections spaced

equidistant apart corresponding to the spacings of the perforations in the edge borders of the picture ribbon or strip, a cross-rod supporting the plates one at each end thereof, an arm or bar carrying the cross-rod and having a reciprocating and oscillating movement given thereto, and means for giving the arm or bar its reciprocating and oscillating movements for the engagement of the plates to intermittently advance the ribbon or strip, substantially as described.

11. The combination in a picture exhibiting and taking machine, of a picture ribbon or strip having on each side an edge border provided with perforations spaced equidistant apart, a pair of upper and a pair of lower feed wheels or disks, each wheel or disk provided with teeth or projections spaced equidistant apart corresponding to the spacings of the perforations in the edge borders of the picture ribbon or strip, a sleeve for each pair of feed wheels or disks having the wheels or disks fixed thereon, a rotatable shaft for each sleeve endwise slidable in the sleeve, an interlock between each shaft and sleeve, a

sprocket-wheel on one end of each shaft, a sprocket-chain running over the sprocket-wheels, a driving means for the lower rotatable shaft for simultaneously revolving the feed wheels or disks and causing the teeth or projections thereof to engage with the perforations of the ribbon or strip and continuously advance the same, a pair of plates each plate having teeth or projections spaced equidistant apart corresponding to the spacings of the perforations in the edge borders of the picture ribbon or strip, a cross-rod carrying the plates one at each end thereof, and an arm or bar supporting the cross-rod and having a reciprocating and oscillating movement given thereto, and means for giving the arm or bar its reciprocating and oscillating movements for the engagement of the acting ends of the plates to intermittently advance the ribbon or strip, substantially as described. 35 40 45
